ELECTRIC CURRENT RESPONSIVE DEVICE

Didier Journeaux, West Collingswood, N. J., assignor, by mesne assignments, to Allis-Chalmers Manufacturing Company, Milwaukee, Wis., a corporation of Delaware

Application August 27, 1930, Serial No. 478,035

17 Claims. (Cl. 200—97)

This invention relates to improvements in electro-magnetically operated, current responsive devices of the induction type and particularly to relays actuated upon the occurrence of a variable current condition.

The usual electrical installation is provided with relays operating to disconnect the various portions of the installation upon the occurrence of overloads which may not only disturb operation but actually destroy portions of the installation. When several units of machines are available, the effect of such overloads may be minimized or avoided by providing relays to connect the units in parallel to divide the overload among 15 so many units that the total overload is so distributed as to constitute less than the permissible maximum load on each unit. As soon as the overload has disappeared, the same relays should disconnect the superfluous units to maintain the 20 units at the maximum efficiency. It is, however, necessary to use relays having a characteristic approximately following the permissible load capacity of a machine for the purpose of protecting the machine against overloads of long duration 25 and of values lower than the setting of the overload relays used for disconnecting the machine on short-circuits. Such relays should, however, have a long-time characteristic and their operation should vary not only in function of the degree 30 of overload but also as a function of the load carried by the machine previously to the overload. Thus, for example, if a machine is rated at 1000 kw. with an overload guarantee of 50% for $\frac{1}{2}$ hour following continuous operation at 35 the rated load, the relay used for protecting the machine must have a characteristic such that if the machine has carried 1000 kw. continuously and the load is then increased to 1500 kw., the relay should disconnect after $\frac{1}{2}$ hour operation 40 of such increased load.

However, if the machine has been carrying only 500 kw. continuously and the load is then increased to 1500 kw. the machine should be permitted to carry such increased load for more than 45 the above pre-determined time limit following continuous capacity loading. Thermal overload relays have been used heretofore to provide the above protection against overloads of long duration and to open or close a switch element at certain temperatures and thereby operate to connect or disconnect the machine. Thermal relays are also used in automatic substations for the purpose of starting up additional machines when 50 the total load exceeds the capacity of the ma-

chines in operation and to shut down the additional machines when the load is again reduced.

The thermal relay, however, has a number of disadvantages which result in inaccurate operation. One of such disadvantages is that the 5 operation of the relay is dependent largely upon the ambient temperature. Thus if the relay is adjusted to close its contacts at a certain load and after a certain time-delay for a low ambient temperature, the relay will disconnect the machine at a lower current or after too short a time-delay if the ambient temperature is higher. Conversely, if the relay is adjusted for a higher ambient temperature, it will not function soon enough and the machine will be overloaded for 10 a long time which may result in serious damage thereto. Another disadvantage of the thermal relay is the difficulty of adjustment for the required service conditions due to the fact that it is difficult to duplicate the bi-metallic or other 15 thermostatic element used on account of variations in the properties of the material and the workmanship of each element so that each relay must be adjusted and calibrated individually which process requires considerable time. 20 Changes, during operation, in the properties of the material used in the thermostatic element likewise cause the relay to lose its adjustment 25 after having been in operation for a certain length of time.

It is, therefore, among the objects of the present invention to provide a current responsive electro-magnetic device in which the time required for a movable element to take a predetermined position, in response to a change in the 30 current impressed on the device, depends on the current value preceding the change in current.

Another object of the invention is to provide a current responsive electro-magnetic device responsive to values of current impressed thereon, 35 for relatively long periods of time.

Another object of the invention is to provide a time element electro-responsive device, the action of which is not dependent upon the ambient 40 temperature.

Another object of the invention is to provide a time element electro-responsive device in which an extensive range of movement of the moving element thereof insures a positive and accurate 45 action of the device.

Another object of the invention is to provide a time element electro-responsive device which may be so proportioned as to have an inverse time characteristic or to have any other desired 50 characteristic.

30

35

45

50

55

Another object of the invention is to provide an electro-responsive device which may be used for indicating and for recording continuously, a load demand and/or the maximum of a load demand.

Another object of the invention is to provide an electro-responsive device for operating control circuits in relation to an electrical load demand.

Another object of the invention is to provide an electro-responsive device for disconnecting electric current rectifiers of the vapor type from a load when the gas or vapor pressure in the rectifier becomes excessive.

Objects and advantages, other than those above set forth, will be apparent from the following description when read in connection with the accompanying drawings in which

Figure 1 is a diagrammatic illustration of one embodiment of the present invention partially showing the mechanical construction of the device schematically and the electrical connections thereof, in diagram, particularly,

Fig. 2 is a top cross-sectional view taken on the line A—A of Fig. 3 with a portion of the disc broken away to show the mechanical structure of the device in greater detail,

Fig. 3 is a front elevation showing constructional details of the device,

Fig. 4 is a diagrammatic illustration similar to that shown in Fig. 1, but showing a modification thereof,

Fig. 5 is a partial top view showing a modified contact-making arrangement,

Fig. 6 is a partial front elevation of the device showing the modified contacting arrangement,

Fig. 7 is a top cross-sectional view taken on the line B—B of Fig. 8 and illustrating one means whereby the operating characteristics of the device may be changed, and

Fig. 8 is a partial front elevation further illustrating the means for varying the characteristics of the device shown in Fig. 7.

Referring more particularly to the drawings by characters of reference, the reference numeral 11 designates the core of an electro-magnet, the coil 12 of which is connected with a source of constant alternating voltage designated at 13. The core 11 of the electro-magnet is formed with the pole pieces 14 and 16, each of which is provided with a shading ring 17 and 18 respectively of suitable shape as will be set forth hereinafter. Pole piece 14 is movably mounted on a spindle 19 suitably supported and extending through a portion of the core 11. The spindle 19 carries a contact-making arrangement for suitably controlling circuits which arrangement includes a drum 21 having conductive portions or inserts 22 connected with the common line 23 of the circuits to be controlled (only partially shown), the other lines of which are shown at 24 and 26 as resilient arms carrying rollers moving in contact with the surface of the drum.

The mechanical details may be seen in Figs. 2 and 3 which show that the movable pole piece 14 is rotated by a gear 27 mounted on the spindle 19 and in mesh with gears 28 transmitting the rotation of a driving pinion 29. The driving pinion is mounted on a suitably supported shaft 31 carrying a disc 32 rotating between pole pieces 14 and 16 and which is also under the influence of a second electro-magnet including a core 33 having pole pieces 34 and 36 with shading rings 37 and 38 and a coil 39 connected with a circuit of the apparatus to be controlled as at 41. A pair of permanent magnets 42 and 43 are so

arranged that the disc 32 passes between the poles thereof and the magnets therefor act, as is well-known, to obtain the proper speed characteristics of an induction type relay.

A leaf spring 44 is so mounted on the core 11 as to permit shading ring 17 to engage therewith when the pole piece 14 has been rotated sufficiently thereby again causing engagement of gear 27 with the gears 28, which are disengaged during operation as will be explained hereinafter, when the disc 32 again rotates in counter-clockwise direction. Pole piece 34 is rotatable by hand and is so adjusted as to be able to retain the characteristics of the relay for different values of rated current in conductors 41 by maintaining the torque of magnet 33 at its normal value for different current ratings.

Assuming that the several portions of the entire relay structure are in the position shown in Fig. 3 and that coil 12 is excited, the shading rings 17 and 18 are then so located relative to each other that no torque is produced on the disc 32. Coil 39 being excited in proportion to the current in conductors 41, causes disc 32 to rotate in a clockwise direction. But pole piece 14 is moved in counter-clockwise direction through the action of the gears 27, 28 and 29 thereby producing an increasing torque on the disc tending to rotate the same in a counter-clockwise direction due to the changing relative positions of the shading rings 17 and 18 which torque causes the disc to slow down until the pole piece 14 reaches a position at which the torque exerted by the action of coil 39 is exactly counter-balanced by that of coil 12. Any increase of current in coil 39 repeats the above action until the equilibrium position is again reached and any decrease of current will cause the reverse operation of that above to take place until equilibrium is again reached. The pole piece 14 thus has a definite equilibrium position for each value of current in the coil 39. The time required for pole piece 14 to rotate from one position to another in response to changes in current in the source 41 depends not only on the magnitude of the current but also on the position of pole piece 14 prior to the current change and, therefore, on the preceding load current passing through the current coil 39. The time required, therefore, for pole piece 14 to reach a certain position will be shorter if the preceding current was high and longer if the preceding current was low. The final position of pole piece 14 may be placed in any desired relation to the value of the current in conductors 41 merely by varying the shapes of pole pieces 14, 16 and the shading rings 17, 18. Thus, the displacement of pole piece 14 may be made proportional to the current in conductors 41 or to the square of the current, or to a more complicated function dependent on the purpose in view. In the first instance, a pointer 15 affixed to the drum 21 carried by pole piece 14 will be made to move over a uniformly sub-divided scale 20 calibrated to values proportional to the short time current demand in the conductors 41 and 65 means, such as a second pointer 25 rotatably supported on a bracket 30 and arranged to be actuated by a pusher 35, forming a part of pointer 15 to register the largest displacement 70 of the pointer 15 to indicate the maximum demand. As is usual in so-called demand meters, the response of the moving element is not instantaneous and the rate at which changes in current are followed may be adjusted, usually by varying the position of the drag magnets 42, 43. 75

As the moving element approaches the position of equilibrium the speed thereof decreases according to a law determined by the physical dimensions of the pole pieces 14, 16 and the shading rings 17, 18. The displacement of the moving element is therefore completed only if the current is maintained in conductors 41 for a predetermined length of time. The time necessary for the contacts to close may be inversely proportional to such currents as is usual in an inverse time delay relay, or may follow an arbitrary law also depending on the shapes of the pole pieces 14, 16 and of the shading rings 17, 18. If it is desired to control the operation of an electric current rectifier, by means of the relay heretofore described, the position of the pole piece 14 may be made to follow the pressure in the rectifier tank which pressure should not exceed a pre-determined value in operation of the rectifier. It will be apparent that, if excessive current is maintained for a protracted length of time in conductors 41, or if coil 12 accidentally becomes de-energized, disc 32 will tend to rotate pole piece 14 continually without regard to the normal operating range thereof. Provision has therefore been made to prevent overtravel in that, it will be observed that, a few of the teeth of gear 21 are removed and that the gear rim is slit along a portion of its periphery adjacent the removed teeth and that the free portion is bent downwardly in such a manner that the gear 27 will disengage from the transmitting gear train 28. Gears 28 then rotate without engaging gear 27 and any wear on the gear 27 will occur on the bent portion of such gear and wear of the pinion will occur on a portion not normally in engagement with gear 21. Such rotation is however limited by the removal of portion of the piece of gear 27 as above explained and pinion 28 then slips on the tooth of gear 21 with which it was last meshed. When normal conditions are restored, disc 32 will first rotate in a counter-clockwise direction to return pole piece 14 to a corresponding position and gears 27 and 28 will re-engage under the action of the spring 44.

In the modified form of the system shown in Fig. 4, a current coil 39', connected in series with the coil 39, is arranged on the core 11 adjacent the voltage coil 12 and in opposition therewith to reduce the action of coil 12 as the current increases in conductors 41 thereby accelerating the response of the disc to high current values in the conductors 41 and changing the characteristics of the relay.

A switching arrangement differing from that previously illustrated and above described is shown in top view and in side elevation in Figures 5 and 6 respectively. The drum 21 above described as attached to spindle 19 of the pole piece 14 is here replaced by a rotatable armature 46. The core 11 of the electro-magnet is provided with a member 47 shunting a portion of the flux therethrough. A suitable tilting armature 48 on which a mercury switch tube 49 is mounted, is pivoted on the shunt armature 47 in such position that the armature 46 may complete the circuit from armature 48 to core 11. When armature 46 has been sufficiently rotated to be directly under armature 48, the magnetic flux is forced to shift in such manner as to flow through rotatable armature 46 so that armature 48 tilts thereby opening or closing the control circuits dependent on the arrangement of the contacts in the switch 49. Suitable stops are provided to limit the movement of tilting arma-

ture 48 thereby preventing interference with the free movement of rotating armature 46.

It is, of course, not essential that the movable pole piece be made as a portion of the core 11 and pivoted thereon as above described, but such pole piece may be made as shown in Fig. 7 which illustrates a movable pole piece comprising a rectangular frame 51 filled with iron laminations 52. The frame of pole piece 51, 52 is however attached to the spindle 19 suitably mounted on the core 11 and carrying the drum 21 or other contacting arrangements as immediately above described. There are also many other ways of varying the operating characteristics of the electro-magnet 11, 12 which will readily occur to one skilled in electro-magnet construction and operation and which need not, therefore, be here described in detail; it being sufficient to mention means such as displacing the magnet relative to the disc, progressively shunting the air gap or the entire magnet, etc.

It is evident from the above description that a structure according to the present invention may be provided with as long a time delay as may be required by proper dimensioning of the electro-magnets and of the gears. It will also be seen that the operating time depends not only on the load current but also on the position of movable pole piece 14 which depends on the previous load current carried by the relay. It will be seen from the above that the present relay has all of the elements necessary to give it the characteristics of a thermal relay without having the disadvantages inherent in such thermal relays. A relay of the character herein described and to be hereinafter claimed is not affected by changing ambient temperatures because the operation thereof is independent of temperature. The operation of the relay being based on mechanical and electro-magnetic principles similar to those employed in watt-hour-meters and induction type relays, which are well-known to the art, the relay has a greater accuracy than a thermal relay. The characteristics of the relay can be determined accurately before construction thereof thus facilitating correct setting for any required condition and such characteristics or setting will not change with age as is the case in thermal relays. The relay will therefore retain its adjustments and its accuracy of operation.

Although but a few embodiments of the present invention have been illustrated and described, it will be apparent to those skilled in the art that various changes and modifications may be made therein without departing from the spirit of the invention or from the scope of the appended claims.

The invention claimed is:

1. In a device of the character described, the combination of an electro-magnet responsive to momentary load conditions of an electric circuit, a disc mounted to be rotated by said electro-magnet, a second electro-magnet having an element adjustable to position in dependence upon the instant load conditions of said circuit in time in dependence upon prior load conditions thereof, and means for controlling an electric circuit, said disc and element cooperating to actuate said circuit controlling means.

2. In a device of the character described, the combination of an electro-magnet responsive to the load conditions of an electric circuit, a disc mounted to be rotated by said electro-magnet, a second electro-magnet having a movable pole adjustable to position in dependence upon the

- instant load conditions of said circuit in time in dependence upon the prior load conditions thereof, and a gear train connecting said disc and the said movable pole, said gear train being formed 5 to prevent over-travel of said disc and to disengage once per revolution of the movable pole of said electro-magnet to prevent over-travel of said disc, and means for causing reengagement of said gear train.
- 10 3. In a device of the character described, the combination of an electro-magnet responsive to the load current conditions of an electric circuit, a disc mounted to be rotated by said electro-magnet, a second electro-magnet cooperating 15 with the first said electromagnet to control the rate and extent of rotation of said disc in dependence upon prior and instant load conditions of said circuit, and means magnetically operated by joint action of said disc and said 20 second electro-magnet to actuate a switch element.
4. In a device of the character described, the combination of an electro-magnet responsive to the load current conditions of an electric circuit, 25 a disc mounted to be rotated by said electro-magnet, a second electro-magnet, means arranged on the said second electro-magnet for varying the rate of rotation of said disc by the first said electromagnet in dependence upon previous load 30 conditions of said circuit, and means magnetically operated by joint action of said disc and the said second electro-magnet to effect actuation of switch elements.
5. An electro-magnetic responsive device comprising means exclusively responsive to the momentary load conditions of an electric circuit, 35 an element adjusted to a position in dependence upon previous load conditions of the electric circuit, constant voltage responsive means cooperating with the first said means to adjust said element to a different position in dependence upon the instant load conditions of said circuit in time in dependence upon the previous and instant load conditions of the electric circuit, and 40 switching means controlling the electric circuit, a portion of the second said means being movable by said element and cooperating therewith to operate said switching means.
6. An electro-magnetically responsive device 45 comprising an electro-magnet exclusively responsive to the load conditions of an electric circuit, a disc inductively adjusted to position in dependence upon previous load conditions of the electric circuit, a constant voltage responsive electro-magnet cooperating with the first said magnet to adjust said disc to a different position dependent upon the instant load conditions of said circuit in time in dependence upon the previous and instant load conditions thereof, 50 and switching means for controlling the electric circuit, a portion of the second said electro-magnet being movable by said disc and cooperating therewith to operate said switching means.
7. In an electro-magnetically operated device, 55 the combination of electro-magnetic means responsive to the load conditions of an electric circuit, a disc inductively adjusted to positions in dependence upon load conditions of the electric circuit prior to the load conditions thereof at any given moment, constant voltage responsive electro-magnetic means cooperating with the first said means to adjust said disc from said position to a different position in dependence upon the instant load conditions of said circuit 60 in time in dependence upon the previous and in-
- stant load conditions of the electric circuit, the last said electro-magnetic means having a movable pole, and switching means for controlling the electric circuit, the movable pole of the second said electro-magnetic means being movable by 5 said disc and cooperating therewith to operate said switching means.
8. In an electro-magnetically operated device, an electro-magnet responsive to the current conditions in an electric circuit, a disc mounted to 10 be rotated by said electro-magnet, a second electro-magnet having an element adjustable to a position in dependence upon current conditions in said circuit prior to the current conditions thereof at any given moment, the said element 15 being operable to vary the rate of rotation of said disc by the first said electromagnet, and means connecting said disc with the said element, the said means preventing over-travel of said element. 20
9. In an electro-magnetically operated device, an electro-magnet responsive to the load conditions in an electric circuit, a disc mounted to be rotated by said electro-magnet, a second electro-magnet having a movable pole positioned by said 25 disc responsive to load conditions in the electric circuit prior to the load conditions therein at any given moment, a gear train connecting said disc and said movable pole, said gear train being formed to prevent over-travel of said movable 30 pole, and means operable by said movable pole to indicate operation of the device.
10. In a device of the character described, an element rotatable in clockwise and counterclockwise directions, an electro-magnet for imparting 35 a torque to said element to cause movement thereof in one of said directions responsive to and in dependence upon a condition of an electric circuit, a second electro-magnet for imparting a torque to said element to cause movement 40 thereof in the other of said directions, and means actuated responsive to movement of said element for varying the torque imparted thereto by the said second electro-magnet. 45
11. In a device of the character described, a disc rotatable in two directions, an electro-magnet for imparting a torque to said disc to cause rotation thereof in one of said directions responsive to and in dependence upon a condition of an electric circuit, a second electro-magnet for imparting 50 a torque to said disc to cause rotation thereof in the other of said directions, and means actuated responsive to rotation of said disc for varying the torque imparted thereto by the said second electro-magnet. 55
12. In a device of the character described, a disc rotatable in two directions, an electro-magnet operable to impart a torque to said disc to cause rotation thereof in one of said directions, a second electro-magnet operable to impart a 60 torque to said disc to cause rotation thereof in the other said directions, and means actuated by said disc for varying the torque imparted thereto by the said second electro-magnet. 65
13. In a device of the character described, a disc rotatable in two directions, an electro-magnet operable to impart a torque to said disc to cause rotation thereof in one of said directions, a second electro-magnet operable to impart a torque to said disc to cause rotation thereof in 70 the other said directions, and means actuated by said disc operable to vary the rate of rotation thereof responsive to the torque imparted thereto by the first said electro-magnet. 75
14. In a device of the character described, an 75

element rotatable in clockwise and counterwise directions, electromagnetic means variably energized responsive to and in dependence on variations in conditions of an electric circuit for causing movement of said element in one of the said directions, electro-magnetically actuated means for causing movement of said element in the other of said directions, and means actuated responsive to movement of said element for varying the action of the second said means thereon.

15. In a device of the character described, an element rotatable in clockwise and counterclockwise directions, electromagnetic means variably energized responsive to and in dependence on variations in the conditions of an electric circuit for imparting to said element a torque proportional to the energization of said means, electromagnetic means energized independently of said circuit for imparting a torque to said element tending to cause movement thereof in the other of said directions, and means actuated responsive to movement of said element in either of said directions for varying the torque imparted thereto by the second said means.

25. 16. A demand indicator comprising in combination, a pair of torque-producing mechanisms acting in opposition, one of said mechanisms hav-

ing a torque proportional to the momentary value of the quantity the demand for which is to be indicated and the other of said mechanisms having an adjustable torque, a member acted upon jointly by said torque-producing mechanisms and movable in response to unbalance in their actions, and movable means for adjusting the torque of said latter torque-producing mechanism, so connected to said movable member as to be moved thereby in a direction required to balance the action of said torque-producing mechanisms.

17. A demand indicator comprising in combination a pair of torque-producing mechanisms acting in conjunction, one of said mechanisms having an output proportional to the momentary value of a quantity, the demand for which is to be indicated, and the other of such mechanisms having an adjustable output, an adjustable device acted upon jointly by said torque-producing mechanisms arranged to have its adjustment varied when said mechanisms act thereon unequally, said device being so connected to said adjustable torque-producing mechanisms as to vary the output thereof in the direction required to equalize the action of said torque-producing mechanisms.

DIDIER JOURNEAUX.
